CLAIM

The ornamental design for a nesting table, as shown and described.

DESCRIPTION

FIG. 1 is a front, right side, top perspective view of a nesting table showing my new design;

FIG. 2 is a rear, left side, bottom perspective view therof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front, right side, top perspective view showing the nesting table in use wherein two sections of the nesting table have been removed from the main housing portion of the nesting table.

The broken lines depict portions of the nesting table that form no part of the claimed design.
